FIG. 1 is a perspective view of a combination pegboard and slot wall panel showing my new design;

FIG. 2 is a front elevational view thereof, the rear being a mirror image of that shown;

FIG. 3 is a top plan view thereof, the bottom being a mirror image of that shown;

FIG. 4 is a right side elevational view thereof, the left side being a mirror image of that shown;

FIG. 5 is an enlarged fragmentary front elevational view thereof of the upper right portion; and,

FIG. 6 is an enlarged fragmentary vertical cross-sectional view thereof, taken along line **6-6** of Fig. 1. The broken-line disclosure around the perimeter is understood to represent an unclaimed boundary.**1 Claim, 4 Drawing Sheets****FIG. 1**
